(57) **CLAIM**

The ornamental design for an artificial fence, as shown and described.

DESCRIPTION

FIG. 1 is a perspective view of an artificial fence showing my new design;

FIG. 2 is a front view thereof;

FIG. 3 is a rear view thereof;

FIG. 4 is a side view thereof;

FIG. 5 is another side view thereof;

FIG. 6 is a bottom view thereof; and,

FIG. 7 is a top view thereof.

The invention pertains to an ornamental design for an article of manufacture. The article is not limited to the scale shown herein.
